ABSTRACT OF THE DISCLOSURE

An electric switch comprises a permanent magnet mounted on a guiding structure so that it can move between two poles of an electromagnetic system. The magnetic system can be energized by means of coils to move the permanent magnet between the poles, and in the absence of such energization the magnet is held against a pole due to its own field. A switch structure having magnetic contacts is positioned near the permanent magnet, so that in one position of the magnet (i.e. against one pole) the contacts are open and in the other position of the magnet the contacts are closed. The switch structure can be a reed switch or it can consist of a magnetic ball adapted to bridge magnetic contacts.

The invention relates to an electric switch comprising at least one set of cooperating magnetically conducting contact members arranged in an envelope and an electromagnetic energization system by the energization of which the said contact members can be set from the open condition in the closed condition, or conversely, the said contact members being maintained in said condition when the energization is removed.

An electric switch of the above described type is known in which two magnetically conducting reeds overlapping each other with their extremities and arranged in an envelope can be made to contact one another or the contact may be interrupted by a pulsatory energization, lasting a few tens of micro seconds, of a yoke consisting of a magnetically conducting material having a certain degree of hysteresis. Such a bistable switch has the drawback that a yoke is required of a particular type of magnetic material while in addition the very short energization time is not necessary for many applications.

It is the object of the invention to provide an electric switch of the type mentioned in the preamble which does not exhibit the above-mentioned drawback, can be manufactured economically, and has further advantages.

The electric switch of the above described type according to the invention is characterized in that by the electro-magnetic energization system a self-supporting movable permanent magnet which is guided in its direction of movement can be made to reciprocate between two poles of the energization system consisting of a magnetically conducting material and determining two end positions of the magnet, the said permanent magnet comprising a permanent pole at each of its extremities facing the said two poles of the energization system and being held against a pole of said system by the field of such a permanent pole in the non-energized condition of the energization system, the said permanent magnet acting in its end positions differently upon a set of cooperating contact members in such manner that a set of cooperating contact members is in the open condition in one end position of the magnet and is in the closed condition in the other end position of the magnet.

2

The energization of such a switch is not critical, the direction thereof determines the position which the magnet will take and consequently the condition of the contacts. The contact pressure is independent of the energization. As a result of the self-supporting arrangement of the magnet and hence the absence of separate guiding members carried by said magnet, the moving mass is restricted as much as possible. The mechanical structure of such a switch can be very simple.

In a further elaboration of the electric switch according to the invention the magnet surrounds at least one envelope and is slidable along it and the energization system comprises a pole located between the two poles and having an aperture through which the magnet is slidable, the magnetic potential of the two outer poles of the energization system with respect to the inner pole being substantially the same when the yoke is energized. As a result of this a high-speed bistable electro-magnetically operable switch of a compact structure is obtained. This switch is particularly suitable, for example, for use in a so-called coordinate switch.

In order that the invention may readily be carried into effect a few examples thereof will now be described in greater detail, by way of example, with reference to the accompanying drawings.

For a better understanding the examples are not drawn to scale.

FIGURE 1 of the drawings shows a cross-section through a switch according to the invention comprising lug contacts arranged along an operating magnet movable by a bipolar energization system.

FIGURE 2 partly shows a cross-sectional view and partly a dissymmetrical projection of a switch according to the invention having a three-pole yoke and an annular magnet which surrounds an envelope which comprises contact members and a contact ball.

FIGURE 3 is a dissymmetrical projection of a coordinate switch according to the invention comprising magnetic ball contacts which can be operated by an energization system having magnetically conducting strips.

FIGURE 4 is an elevation of parts of the three successive plates of an energization system of a coordinate switch according to the invention comprising three plates and a number of transverse strips of magnetically conducting material.

FIGURE 5 is a cross-sectional view of a coordinate switch having an energization system taken along the line V—V of FIGURE 4.

Referring now to FIGURE 1, reference numeral 1 denotes a disc-shaped permanent magnet. The magnet 1 is self-supporting about a magnetically insulating rigidly secured shaft 3 and reciprocable between the poles 5 and 7 of an energization system. The poles 5 and 7 are constituted by the collars of sleeves 9 and 11, respectively, of magnetically conducting material, for example, soft iron, secured about the shaft 3, for example, by gluing. The poles 5 and 7 can be energized by coils 13 and 15, respectively, arranged around the sleeves 9 and 11, respectively. A number of envelopes 17, 19 comprising contact lugs of magnetically conducting material 21, 23, 25, 27 are arranged around the magnet 1. The shaft 3 and the envelopes 17 and 19 are supported by the plates 29 and 31 of magnetically insulating material.

The operation of the switch is as follows. In the position shown the magnet 1 is held against the pole 5 by its north pole N facing said pole 5 of the energization system. By the field of the magnet 1 the contact lugs 25 and 27 are held attracted against one another with their overlapping ends. The contact lugs 21 and 23 are open because the field of the magnet 1 produces substantially no magnetic potential difference between said lugs. By the

energization of the coils 13 and 15 the poles 5 and 7 are magnetized to form, for example, north poles. In that case the north pole N of the magnet 1 is repelled by the pole 5 and its south pole S facing the pole 7 is attracted by said pole 7 and is displaced until it engages the pole 7. When the energization is removed the magnet 1 remains attracted against the pole 7 as a result of its own field. The lugs 21 and 23 now contact one another and the contact between the lugs 25 and 27 is interrupted. A short-lasting energization of the coils 13, 15 in the reverse direction will produce again the position as shown. For convenience a disc-shaped magnet 1 is discussed in this case. To reduce the mass of such a magnet it may be provided, for example, with recesses or even be composed of two coaxial magnetic rings held together by a joint of a light-weight material. By a correct proportioning, design and arrangement of the various components of the switch a relatively much smaller diameter of the magnet disc and a relatively smaller track between the final positions of the magnet disc can be achieved than is shown, for clarity, in the figure.

In FIGURE 2 an annular magnet 33 is self-supporting and movable about an envelope 35. The final positions of the magnet 33 are determined by two poles 37 and 39 of a magnetically conducting yoke 41 having three limbs in the form of an E. The magnet 33 can move through an aperture 42 in a third pole 43 in the central limb of the yoke. On their side facing the magnet 33 the poles 37 and 39 of the yoke 41 comprises spacing plates 44, 45 of a shock-absorbing magnetically insulating material, for example, polyethylene terephthalate, against which the magnet 33 resets in its final positions. The central limb of the E-shaped yoke 41 comprises an energization coil 47. The envelope 35 about which the magnet 33 is slideable comprises a number of magnetically conducting contact members 49, 51, 53, 55 and a magnetically conducting contact ball 57 which can be operated by the flux inside the magnet 33.

The operation of the switch is as follows. In the position shown and in the non-energized condition of the coil 47 the magnet 33 remains attracted, by a part of its own flux (holding flux), against the pole 37 which is lined with a spacing plate 44 to restrict the holding flux.

Under the influence of the flux inside the magnet 33 the contact ball 57 is located against the contact members 49 and 51 and connects them together. When the coil 47 is energized in such manner that the holding flux of the magnet 33 is counteracted and exceeded by the energization flux, the magnet 33 disengages the pole 37 and moves towards the pole 39. During this movement the force exerted on the magnet 33 increases more and more as a result of the increasing distance to the pole 37. As a result of this the movement of the magnet 33 from the pole 37 to the pole 39 is a very fast one. The contact ball 57 is taken along by the flux inside magnet 33, and the magnet 33 and the ball 57 then take the position denoted in broken lines. Then the contact members 53 and 55 are connected together and the contact members 49 and 51 are open. When the energization is removed the magnet 33 is held against the pole 39 by its holding flux emerging from the end face facing that pole. The contact ball 57 then remains in the broken-line position. A short-lasting energization of the coil 47 in the reverse direction will again produce the original condition.

The distance between the poles 37 and 39 is determined by the proportions of the magnet 33 and the distance which the ball 57 has to cover between the oppositely located pairs of contacts. These distances may be small so that the switch may have a compact structure. The coil 47 which is shown around the central limb of the yoke may also be divided around the outer limbs or around the parts joining the central limb and the outer limbs. Instead of an envelope with a ball contact, of course, also an envelope with, for example, a lug contact or a sliding armature contact may be used. The magnet 33 may furthermore comprise, for example, more holes so

that a number of contacts can be operated simultaneously by said magnet.

A switch as described here may be constructed favourably, for example, as a mounting unit for a larger circuit arrangement with printed wiring, for example, a coordinate switch. In that case the energization coil may be constructed from several individually energizable parts.

In FIGURE 3, three groups of magnetically conducting strips 61, 63, 65, 67, 69, 71; and 73, 75, 77 are arranged in three layers. The strips 61, 63, 65, 67, 69 and 71 in the outer layers extend in the same direction and the strips 73, 75 and 77 in the inner layer extend at right angles to those in the outer layers. All the strips of the outer layers are connected to the same strip 75 (first reference strip) by magnetically conducting transverse members 79, 81, 83, 85, 87 and 89. The strips of the inner layers are connected to two oppositely located strips 63 and 69 of the outer layer (second and third reference strips) by magnetically conducting transverse members 91, 93, 83, 85, 95 and 97. Around the transverse members 79, 81, 87, 89, 91, 93, 95 and 97 which connect all the strips to the reference strips 63, 69, 75, coils are arranged which are diagrammatically shown in the figure and denoted by 99, 101, 103, 105, 107, 109, 111, and 113, respectively. Coils are also arranged around the transverse members 83 and 85 which connect the reference strips 63, 69 and 75 together which coils are diagrammatically shown and denoted by 115 and 117. The assembly constitutes a central energization system for the intersections of the strips 61, 63, 65, 67, 69, 71, 73, 75 and 77. At these intersections envelopes 119, 121, 123 and 125 are arranged which comprise contact members which can be operated by a magnet. Around the envelopes 119, 121, 123 and 125 self-supporting annular magnets 127, 129, 131 and 133 are slideable through holes 135, 137, 139 and 141 in the strips of the inner layer under the influence of fields produced by the energization system in a manner as described with reference to FIGURE 2. The position of the annular magnets determines the position of a number of magnetically conducting contact balls 142, 143, 145 and 147 and hence the condition of the contact members in the envelopes 119, 121, 123 and 125.

The operation of the above described coordinate switch is as follows:

When the coils are not energized and are in the condition shown, the annular magnets 129, 131 and 133 engage the strips 61 and 65 and the magnet 127 engages the strip 67 against which they are held by their own fields. As a result of the magnetically conducting transverse members and the reference strips all the strips have the same magnetic potential. When a pair of coils 103, 105 is energized, a magnetic potential difference may be produced between the strips 71 and 65, respectively, and the first reference strip 75. This is effected in such manner that the strips 65 and 71 obtain the same magnetic potential with respect to the first reference strip 75. The strips 77 and 73 now hold the magnetic potential of the first reference strip 75 as a result of the magnetic connection via the transverse members 83 and 85, the reference strips 69 and 63, and the transverse members 91, 93 and 95, 97. A magnetic potential difference is formed at the area of the envelopes 123 and 125. The value of this potential difference must be approximately half the value M which is required to cause the annular magnets 131 or 133 to be moved, so approximately $\frac{1}{2}M$. If by means of the pair of coils 107, 109 a magnetic potential difference of $\frac{1}{2}M$ is applied between the second and third reference strips 63, 69 (which as a result of the transverse members 83, 85 have the potential of the first reference strip 75) and the strip 73, the potential difference between the strips 65 and 71 and 73, respectively, totally becomes

$$(\frac{1}{2}M + \frac{1}{2}M) = M$$

This value M causes the magnet 131 to be displaced from the strip 65 to the strip 71 and thus to vary the position

of the contact members in the envelope 123. The potential difference between the strips 65 and 71 and 77, respectively, and the strips 61 and 67, respectively (via reference strip 75 and transverse members 79 and 81) and 5 73 now is $\frac{1}{2}M$, so that no influence can be exerted on the position of the magnets 133 and 127. Energization of the pairs of coils 103, 105 and 107, 109 in the reverse direction produces a magnetic potential difference $-M$ between the strips 65 and 71 and 73, respectively, so that the magnet 131 again returns to the position shown without the other magnets varying their positions.

In order to make the magnetic potential difference between the strips smaller at the area of the intersections not to be operated so that a larger spreading in the composing elements of the coordinate switch can be permitted, a 10 magnetic pre-energization of, for example, $-\frac{1}{3}M$ may be set up between the reference strips 75 and 63 and 69, respectively, by means of the pair of coils 115, 117 during energizing a desired intersection to be operated, for example, the above described intersection of the strips 65, 73, 20 71. The energization of the pairs of coils 103, 105 and 107, 109 must then be increased so that they each supply a magnetic potential difference of $\frac{2}{3}M$. A resulting potential difference of $(\frac{2}{3}M - \frac{1}{3}M + \frac{2}{3}M) = M$ is then applied to the intersection to be operated and the magnet 131 in question is displaced while a magnetic potential difference of only + or $-\frac{1}{3}M$ is applied to each of the intersections not to be operated. This is a more favourable value than in the above described case of the non-energized condition of the coils 115, 117 in which the potential difference between the strips of an intersection not to be operated could be + or $-\frac{1}{2}M$.

The central arrangement of the reference strips has the advantage that the distance from the reference strips to the intersection and consequently the magnetic resistance remains as small as possible without energization coils having to be provided at several points, for example, as is normal, along the circumference of the switch. Of course, a plurality of contacts may be arranged per intersection which are operated collectively by one magnet.

In FIGURES 4 and 5 three magnetically conducting plates 151, 153, 155 consisting, for example, of soft iron, are spaced apart by magnetically conducting transverse strips 159. The central plate 153 comprises lugs 161 cut or etched in the plate. These lugs 161 are separated from the plate 153 for the greater part by an air gap 163. A number of envelopes 165 having a contact ball 169 which can be moved by an annular magnet 167 are arranged between the outer plates 151 and 155. The envelopes 165 comprise magnetically conducting contact members 171 with which they are secured in an insulating manner between the outer plates 151, 155 in a manner not shown (for example, soldered with the contact ends in a printed circuit board). The envelopes 165 extend through holes 173 in the lugs 161. The holes 173 are sufficiently large so as to pass also the annular magnets 167 movable around the envelopes 165. The lugs 161 can be energized by two groups of coils 175, 177 which are arranged round the central plate 153. The magnets 167 are held against one of the plates 151 or 153 by their own fields when the coils are not energized, on which plates spacing plates of shock-absorbing magnetically non-conducting material 179, for example, polyethylene terephthalate, are secured, for example, by gluing.

The operation of the coordinate switch is as follows.

By the simultaneous energization of a coil 175 and a coil 177 a lug 161 along which the two coils extend is brought at a sufficiently high magnetic potential to move, in the manner described with reference to FIGURE 2, a magnet 167 along an envelope 165 from one outer plate 151 to the other 155, or conversely, and thus to determine the position of the corresponding contact ball 169. All the other lugs are then insufficiently energized (in fact they only obtain approximately half of the magnetic potential required therefor) to displace a magnet. So an arbitrary contact may be set in the desired position.

The construction of the switch and the shape of the components is such that a compact, reliable and cheap coordinate switch is obtained which is particularly suitable for use, for example, in a telephone exchange.

The transverse strips 159 are necessary to form a magnetic circuit as described with reference to FIGURE 2 but they also have a screening effect so that interference fields as a result of energization of one of the lugs at the area of a number of adjacent lugs are restricted. The number of contacts to be operated per switch may easily be adapted to the needs with this type of switch by suitable choice of the proportions of the plates 151, 153, 155 and the transverse strips 159. The groups of coils 175, 177 may be located, instead of around the whole plate 153, for example, also only at the area of the lugs 161 around said lugs and further extend fully along the same side of the plate 153.

When using one of the described coordinate switches, for example, as a preselector in a connection circuit in a telephone exchange, the contacts in a row or column on the same side of the switch (make contacts) may serve for putting through the line, and the contacts of the whole row or column in question on the other side (break contacts) may be connected in series and serve as a separating contact, for example, for a line relay or other detection circuit.

What is claimed is:

1. An electric switch comprising at least one set of magnetically conducting contact members adjacent each other and having open and closed positions; an energization system including a pair of outer poles magnetically coupled and disposed adjacent said contact members; a mediate pole located between said outer poles, magnetically coupled thereto, and having an aperture; coil means for energizing said outer poles equally; a permanent magnet disposed to reciprocate between said outer poles and through said aperture and having permanent poles at each of its extremities for holding said magnet against one of the outer poles when said coil is not energized thereby locking said contacts in one of said positions and whereby energizing said coil causes said magnet to move to the other outer pole locking said contacts in the other of said positions.

2. An electric switch as claimed in claim 1, further comprising a multiple arrangement of contacts each with corresponding magnets, and at least two groups of energization coils, each of the magnets being movable only by the simultaneous energization of at least one coil of each of the groups at will.

3. An electric switch as claimed in claim 2, wherein the energization system comprises a number of magnetically conducting strips arranged regularly in three layers and intersecting one another, the strips in the outer layers being directed equally and those in the central layer being directed at right angles to that of the outer layers, an intersection of three strips located in different layers constituting the operating poles for said movable magnet, each of the strips of the outer layers being connected by a magnetically conducting transverse member to the same first reference strip of the inner layer and each of the strips of the inner layer being connected by a magnetically conducting transverse member to two oppositely located second and third reference strips of the outer layers, a number of magnetically conducting transverse members being provided with energization coils.

4. An electric switch as claimed in claim 3 wherein the transverse members which connect the three said reference strips are provided with an energization coil.

5. An electric switch as claimed in claim 3, wherein at least one of the said reference strips is arranged centrally in the energization system.

6. An electric switch as claimed in claim 2, wherein the energization system comprises three stacked magnetically conducting plates which are spaced apart by

magnetically conducting transverse strips, the central plate comprising a number of lugs arranged according to a pattern and cut in the plate so as to be partly magnetically insulated therefrom, each of said lugs having a hole for passing permanent magnet around said contacts and said lugs being energizable by groups of coils arranged on said central plate.

7. An electric switch as claimed in claim 1 wherein said contacts comprise at least one pair of parallel arranged magnetically conducting fixed contact members with which a ball which is movable by the field of the magnet can be contacted.
